UNITED STATES PATENT OFFICE.

GEORGE W. BOWMAN, OF SALEM, MISSOURI.

BRACE.

1,012,509.

Specification of Letters Patent.

Patented Dec. 19, 1911.

Application filed May 12, 1911. Serial No. 626,790.

To all whom it may concern:

Be it known that I, GEORGE W. BOWMAN, a citizen of the United States, residing at Salem, in the county of Dent and State of Missouri, have invented a new and useful Brace, of which the following is a specification.

This invention relates to an improvement in braces for the bows of vehicle tops.

10 The primary object of said invention is to provide a simple and economically manufactured device of this character which may be readily positioned on one of the top supports and which will conveniently support 15 said top when in its folded position.

With the foregoing and other objects in view which will appear as the description proceeds, the invention resides in the combination and arrangement of parts and in 20 the details of construction hereinafter described and claimed, it being understood that changes in the precise embodiment of the invention herein disclosed can be made within the scope of what is claimed without 25 departing from the spirit of the invention.

In the drawings,—Figure 1 is a side elevation showing a buggy top equipped with the brace, Fig. 2 is a perspective view of the brace, Fig. 3 is a sectional view of the locking device; Fig. 4 is an end view of said locking device in its closed position; and Fig. 5 is a side elevation of the same.

The device consists of a beam 10, one end of which is bent to form a supporting arm 11, the end portion of which is concaved and adapted to receive the bow 12. A central support 13 is either formed integral or secured to the member 10, said support being provided with a hook 14 which can 35 be formed integral with the support 13; thus the concaved end of the support 11 contacts with one edge of the bow, while the hook 14 contacts with the other edge. Arranged at the other end of the beam 10 is a support 40 15 similar to the support 11, the same being provided with a retaining hook 16 disposed in the same manner as the hook 14 overhanging the end portion of the support 15. The support 15 is reduced to receive a locking device 17, the edge 15' of the support and the edge 17' of the locking device being beveled, a securing device 18 pass-

ing centrally through the upper portion of the support 15 in the central portion of the member 17, thus allowing the member 17 55 to swing to the position shown in Fig. 5, the face 19 of the member 15 being beveled to agree with one of the beveled ends 20 of the latch member 17, thus permitting its movement in one direction and restricting 60 its movement in the other direction; the other end of said latch member being beveled, its face being concaved and provided with corrugations 21 which, when the latch member is swung to the position shown in 65 Fig. 2 securely grip the bow, preventing the displacement of the brace and preventing movement of the same on the bow. Secured at a point immediately below the surface 70 19 with which the end portion of the latch member 20 contacts, is a spring pressed rotary latch member which said member being elongated and when in its locked position it contacts with the end portion of the latch member 17, the same being thus prevented from movement in either direction. 75

It will be noted from the foregoing that a device of this character, while simple in construction, will be found efficient in practice, the brace being readily and conveniently positioned on the bow, the same being of a construction which will effectually support the top.

What is claimed is:—

1. A device of the class described consisting of a beam, a plurality of right angular extensions arranged on said beam, said extensions being provided with securing devices arranged to contact with the bow of a vehicle hood, one of said extensions being provided with a pivoted latch member, said latch member having a corrugated face, and means for holding said latch member against movement. 85 90

2. A device of the class described consisting of a beam, said beam being provided with a plurality of supports, one of said supports being formed with a hook arranged to embrace one edge of a vehicle bow, and a pivoted latch member co-acting with said 100 hook to engage the opposite face of said bow, and means for holding said pivoted portion in locked position. 95

3. A device of the class described consist-

ing of a beam, said beam being provided with a plurality of extensions adapted to engage the bow of a vehicle hood, a hook formed on one of said extensions, said extension being reduced, its reduced portion being beveled and a beveled latch member pivotally supported by said reduced portion.

In testimony that I claim the foregoing as my own, I have hereto affixed my signature in the presence of two witnesses.

GEORGE W. BOWMAN.
